Robert S. Blair Inventor

UNITED STATES PATENT OFFICE.

ROBERT S. BLAIR, OF SOUTH ORANGE, NEW JERSEY.

HOLDING DEVICE FOR DOORS AND THE LIKE.

Application filed May 10, 1915. Serial No. 26,996.

To all whom it may concern:

Be it known that I, ROBERT S. BLAIR, a citizen of the United States, and residing at South Orange, in the county of Essex and State of New Jersey, have invented a new and Improved Holding Device for Doors and the like, of which the following specification is a full disclosure.

This invention relates to holding devices. 10 One of the objects thereof is to provide a simple and practical device for holding a door or the like securely in position. Another object is to provide a device of the above nature which shall be automatic and 15 reliable in its action. Another object is to provide a device of the above nature in which the various parts are durable and act efficiently without injury to themselves or coacting parts. Other objects are to provide 20 a device of the above nature which shall be inexpensive and readily manipulated.

Other objects will be in part obvious and in part pointed out hereinafter.

This invention accordingly consists in the 25 features of construction, combinations of parts, and in the unique relations of the members and in the relative proportioning and disposition thereof; all as more completely outlined herein.

30 In the accompanying drawing, in which is shown one of the various possible embodiments of this invention,

Fig. 1 is a sectional elevation of a holding device;

35 Fig. 2 is a detached, sectional view of certain parts shown in Fig. 1; and

Fig. 3 is a side elevation of the parts shown in Fig. 2.

Similar reference characters refer to similar parts throughout the several views of the drawing.

Referring now to Fig. 1 of the drawing, there is shown a door 1 to which is secured a fitting 2, as by means of the countersunk 45 screws 3. This fitting comprises a recess 4 provided at its lower end with a shoulder 5 and preferably with a pair of guiding ribs 6 which may be cast integral therewith. The lower end of the fitting is formed into a 50 recess 7 for the purpose hereinafter described.

Mounted within fitting 2 is a slidable rod or spindle 8 provided at its upper end with a button 9 and having its lower end riveted to a cup-shaped member 10, shown more 55 clearly in Fig. 3. The rod 8 has extending therethrough a pin 11 one end of which pref-

erably rests between the guiding ribs 6 and between this pin and the shoulder 5 there is compressed a spiral spring 12 which tends to throw the rod into its uppermost position.

Upward movement of the rod 8 is normally resisted by a latch 13 hinged to the fitting as at 14 and tilted upwardly by the spring 15. This latch, in which the rod 8 has a loose fitting, is tilted or clamped by the spring 15 to bind on the rod and resist movement in an upward direction. A downward movement, however, as by pressure on the button 9, is unopposed as this action tends to swing the latch into a horizontal position. The rod 8 thus moves downwardly without twisting due to the position of the pin 11 between the guide ribs 6, and when it has been depressed to the desired point it is automatically held in such position until the latch 13 is depressed permitting rod 8 with its associated parts to rise until the cup-shaped member 10 comes into contact with the curved walls of the recess 7.

Within the cup 10 is secured in any desired manner a plug 25 of rubber, or preferably of a firmer composition such as celluloid. This device being mounted to swing in the directions indicated by the double arrow 26 is formed to provide a recess 27 extending entirely through its lower portion. Also, as by the incisions 28, there are cut loose flaps 25 at each side and thus provided inclined abutments 30, the lower ends of which act as a floor-engaging member. When it is desired to hold a member, as the door 1, against movement, pressure is applied upon button 9, as by the foot, and rod 8 is thus thrust downwardly. This action, which is unimpeded by the latch 13 as above pointed out, carries by means of the cup-shaped member 10 the floor-engaging device 25 into engagement with the floor. With the device thus thrown against the floor, if there be a tendency to movement in either direction indicated by arrow 26, then one of the abutments 30 has a corresponding tendency to swing about its connection with the upper end of the plug 25 and wedge itself more firmly into engagement with the floor. The parts may be so proportioned that this automatic increase in pressure attains a high value, and even if the abutment 30 swing over into the space indicated by the recess 27 it will be supported and held against further movement in such direction by the

opposite abutment 30 and flap 29. In this manner the door is locked against appreciable movement in either direction. A slight pressure upon latch 13 compressing spring 15 will release the spindle 8 and allow the spring 12 to draw the device up from the floor-engaging position.

As many changes might be made in the above construction, and as many apparently different embodiments might be made of this invention without departing from the scope thereof, it is intended that all features herein described or shown in the accompanying drawing shall be interpreted as illustrative 15 and not in a limiting sense.

Having thus revealed this invention, I claim as new and desire to secure the following combinations of elements, or equivalents thereof, by Letters Patent of the United 20 States:—

1. In a holding device for doors and the like, a member secured to the door, a floor-engaging device, means on said member adapted to force said device downwardly 25 into engagement with the floor and automatically retain it in such position, and means adapted to release said device and permit it to move upwardly, said device comprising a pair of substantially straight 30 parts adapted yieldingly to engage the floor and respectively to swing into jamming position as the door is moved.

2. In a holding device for doors and the

like, a member secured to the door, a floor-engaging device, means on said member 35 adapted to force said device downwardly into engagement with the floor and automatically retain it in such position, and means adapted to release said device and permit it to move upwardly, said device 40 comprising a unitary member of yielding material having a substantially V-shaped recess parallel with the door and its portions on opposite sides of said recess being shaped to swing into jamming position. 45

3. In a holding device for doors and the like, a member secured to the door, a floor-engaging device, means on said member adapted to force said device downwardly 50 into engagement with the floor and automatically retain it in such position, and means adapted to release said device and permit it to move upwardly, said device comprising a resilient member provided with a V-shaped recess substantially parallel to 55 the door and having incisions spaced from and substantially parallel to the walls of recess.

In witness whereof, I hereunto subscribe my name, as attested by the two subscribing 60 witnesses.

ROBERT S. BLAIR.
